(57) **CLAIM**

The ornamental design for a flexible pointed surgical osteotome blade, as shown and described.

DESCRIPTION

FIG. 1 is a front view of the flexible pointed surgical osteotome blade showing the upper portion attached to an osteotome in its environment of use;

FIG. 2 is an enlarged front view of the flexible pointed surgical osteotome blade shown in FIG. 1;

FIG. 3 is an enlarged rear view of the flexible pointed surgical osteotome blade shown in FIG. 2;

FIG. 4 is a right side elevational view of the flexible pointed surgical osteotome blade shown in FIG. 2;

FIG. 5 is a left side elevational view of the flexible pointed surgical osteotome blade shown in FIG. 2;

FIG. 6 is a top plan view of the flexible pointed surgical osteotome blade shown in FIG. 2;

FIG. 7 is a cross-sectional view of the flexible pointed surgical osteotome blade, taken from the direction of line 7-7 in FIG. 2;

FIG. 8 is a bottom view of the flexible pointed surgical osteotome blade shown in FIG. 2;

FIG. 9 is a rear view of the flexible pointed surgical osteotome blade in its environment of use; and,

FIG. 10 is a right side elevational view of the flexible pointed surgical osteotome blade shown in an alternate configuration of use.

The broken lines in FIG. 1, FIG. 9 and FIG. 10 of the drawings show unclaimed environment only and form no part of the claimed design.

1 Claim, 4 Drawing Sheets
